BALL-MILL FOR CRUSHING ORES.

1,374,410.

Specification of Letters Patent. Patented Apr. 12, 1921.

Application filed August 20, 1919. Serial No. 318,789.

To all whom it may concern:

Be it known that I, MIKAEL VOGEL-JØRGENSEN, civil-engineer, a subject of the King of Denmark, residing in 103 Nylandsvej, 5 Frederiksberg, near Copenhagen, Denmark, have invented certain new and useful Improvements in Ball-Mills for Crushing Ores, of which the following is a specification, reference being had to the accompanying 10 drawing, forming a part hereof.

This invention relates to ball mills for crushing ores.

In many cases a plant for crushing ore consists of a ball mill only in which by 15 means of the same balls the ore is to be crushed from lumps of 75-100 mm. size down to the desired fineness. The balls as a rule are rather large and together with the material to be treated occupy so much room 20 in the drum that the surface of the charge is at a level with the lower edge of the outlet pivot. The working of the mill requires a very considerable accumulation of material in the same, seeing that the ore having been 25 treated is to be flushed out through the outlet pivot with water, and the means, therefore, whereby the crushing fineness is being regulated consists in varying the supply of water in connection with variation of the 30 quantity of material being fed into the mill.

Mills of the said kind are often furnished with a small conical sieve in the outlet, but this sieve is too inaccessible and its sifting area proper is too small to make it act as a 35 regulator for the fineness. The sieve practically only serves like some sort of controller, to fix a limit for the coarseness of the goods having been sifted off, but otherwise it has no influence on the degree of crushing.

40 In treating ore the grinding must preferably be carried on very far, regardless of whether the ore is to be subjected to a following washing out on tables, or separation by means of flotation, or magnetic separation, 45 and when the whole of this comprehensive crushing as described is to be done by a ball mill alone, so that this actually has to also perform the total fine grinding, it really means that a task is exacted from such a

mill for which it is not adapted at all. Further, the immovable, big accumulation of material involves a considerable decrease in the striking action of the balls by falling, which action otherwise is the most advantageous working of the grinding bodies in 55 all kinds of ball mills, the balls being restrained herein by the big, dead mass in the drum. One way and another reduces the quantity of output and increases the consumption of power to an inordinate degree. 60

Of late years the attention has been upon the highly unsatisfactory economy of these mills, and little by little several improved types of ball mills for crushing ores have been constructed in which it has been successfully tried in various ways to obtain a better working. It has for instance been proposed to construct the mill with a large conical sieve widening toward the mill body and being made in one with the outlet 70 bottom, forming part of this, whereby partly the accumulation of materials is reduced and partly the sifting effect improved, but besides the fact that even in a mill of this said construction the material will accumulate as 75 described there is the further drawback in connection with the sifting that the material will have to pass out onto the sieve and, as far as the part is concerned which is not fine enough to pass through this, back to the 80 mill by the same way. For this reason a sieve of this description does not work in a sufficiently effective way.

In some later types of ore crushers sieves are arranged differently in the outlet bottom, but also in these mills the crushing fineness is regulated by accumulation of the material, the working taking place by having the outlet grates covered to a suitable extent from the periphery toward the center 90 whereby the material will accumulate and the fineness of crushing consequently be increased.

Both of the drawbacks mentioned: the accumulation of material and the loading of 95 the mill for an operation for which it is not adapted, the fine grinding, are present also in the later mills. Finally, it applies to all

these mills in common that the sifting always presents the drawback as mentioned in the foregoing that the material which cannot pass through the sieve must return to the mill chamber by the same way by which it went out onto the sieve and, consequently, will render the passage for new material to be sifted difficult, whereby the sieve will be restrained from acting fully in such a way that it is this which regulates the fineness of crushing. Even in the best of these later types of mills it has not been possible to prevent part of the material from being crushed down to the fineness of slurry before it leaves the mill, and in this condition the material is unqualified for the purpose for which it is to be used.

The present invention has for its object firstly to limit the function of the mill to its real specialty, the crushing, and secondly to fit up the sifting system for separating off the sufficiently crushed material in such a way that the sieve will actually act as the desired regulator for the crushing fineness.

For the first purpose the mill is furnished with an outlet bottom having peripherically arranged slits through which the material leaves the mill without having been sifted as soon as it has traveled through the drum, and for the second purpose, the attainment of an efficient sifting action, a special arrangement has been made by means of which the material is led onto a sieve and back from the same by various paths in a continuous course, a circulation being arranged from the mill through a sifting drum and by another path from this back to the mill.

The accompanying drawing illustrates an embodiment of the outlet wall of a mill according to the present invention, in longitudinal section. The continuous exit of the material from the mill as soon as it has traveled through the same is executed through wide grate intervals or slits *c* in the outlet wall *b*. These intervals or slits *c* are placed as near as possible to the outer circumference of the mill in order to avoid an accumulation of material. The material having left the crushing chamber is taken upward by means of lifting shovels *l* and through a hole in the end of the hollow outlet tube *u* of the mill falls down on to a relatively coarse conical sieve *s* where the sufficiently finely crushed material is sifted off.

The part not yet fine enough falls down the screen into a trough *s'* and on other lifting shovels *t*. The shovels *t* transfer the material through channels *t'* to a pipe *v* which extends co-axially with the trunnion *b'*. The discharge pipe *u* extends through the pipe *v*. The inner end of the pipe *v* communicates with the interior of the mill so that the coarse material discharged into said pipe is returned therethrough to the mill

traveling in a direction contrary to the direction of travel of the material through the pipe *u*. The mill is supported by the hollow trunnion *b'* journaled in a bearing *m*.

The quantity of water required for the sifting and for keeping the sieve clean is fed into the sieve cylinder through a pipe *r* which leads the water to the lifting shovels *t* and thus into the mill, so that the requisite amount of water for crushing is always present in the mill chamber.

I claim as my invention:

1. In a grinding mill, in combination with a supporting trunnion for the mill at the discharge end in open communication with the mill, but extending beyond the end wall thereof, a grate adjacent the discharge head through which the material is discharged, a discharge pipe extending through the trunnion and adapted to receive the material from the grate and to convey it beyond the end of the trunnion, a screen supported at the end of the discharge trunnion to receive the material from the discharge pipe, and means to return the coarse material from the screen to the trunnion whence it is conveyed therethrough in a direction counter to the direction of travel through the discharge pipe for return to the mill.

2. In a grinding mill, in combination with a supporting trunnion for the mill at the discharge end in open communication with the mill, but extending beyond the end wall thereof, a grate adjacent the discharge head through which the material is discharged, a discharge pipe extending through the trunnion and adapted to receive the material from the grate and to convey it beyond the end of the trunnion, lifting shovels and channels in the head of the mill to transfer the material from the grate to the discharge pipe, a screen supported at the end of the discharge trunnion to receive the material from the discharge pipe, a trough formed at one end of the screen to receive the coarse material, lifting shovels in the trough and return channels extending from the shovels to the trunnion for the transfer of coarse material from the screen to the trunnion whence it is conveyed therethrough in a direction counter to the direction of travel through the discharge pipe for return to the mill.

3. In a grinding mill, in combination with a trunnion at the discharge end in open communication with the mill, a grate adjacent the discharge head through which the material is discharged, a discharge pipe mounted coaxially within the discharge end trunnion to receive the material from the grate, lifting shovels and channels in the head of the mill to direct the material from the grate to the discharge pipe, a conical screen sup-

ported on the end of the discharge trunnion and rotatable therewith to receive the material from the discharge pipe, a trough formed at the inner end of the screen to receive the coarse material, lifting shovels in the trough and return channels extending from the shovels to the trunnion for the return of coarse material to the trunnion,

said material passing through the trunnion around the discharge pipe into the mill. 10

This specification signed and witnessed this 12 day of April A. D. 1919.
